UNITED STATES PATENT OFFICE.

DAVID WOEHRLE, OF SIOUX FALLS, SOUTH DAKOTA.

FINGER-GUARD BOLT.

SPECIFICATION forming part of Letters Patent No. 437,072, dated September 23, 1890.

Application filed May 22, 1890. Serial No. 352,725. (No model.)

To all whom it may concern:

Be it known that I, DAVID WOEHRLE, a citizen of the United States, residing at Sioux Falls, in the county of Minnehaha and State 5 of South Dakota, have invented certain new and useful Improvements in Mower and Harvester Finger-Guard Bolts; and I do declare the following to be a full, clear, and exact description of the invention, such as will enable 10 others skilled in the art to which it appertains to make and use the same.

My invention relates to an improvement in bolts which are adapted for use in securing the ledger-plates to the finger-guards of harvesters and mowers, as will be hereinafter set forth.

Referring to the accompanying drawings, Figure 1 is a longitudinal vertical sectional view of a finger-guard having the ledger-plate 20 secured thereto by means of my improved bolt. Fig. 2 is a top plan view. Fig. 3 is a bottom plan view; and Figs. 4, 5, and 6 are detail views illustrating different forms of the bolt.

In finger-guards for harvesters and mowers 25 it is very important that the means of securing the ledger-plates in position should leave a smooth even surface on top for the free movement of the sickle-sections back and forth upon them, and it should also make as close a fit or joint as possible to avoid the lodgment of dirt, &c. By means of my improved bolt I secure such a construction, as 30 one end of the bolt is flush with the top of the ledger-plate and the other end is flush or 35 within the lower side of the guard.

In applying the bolt I provide the finger-guard with a vertical perforation 2, which 40 will register with a corresponding perforation 4 in the ledger-plate 3. Fitting within these 45 perforations is a bolt 5, the lower portion of which, or shank 6, is screw-threaded and provided with a head 7, which engages with the lower portion of the guard and prevents it 50 being drawn up through the guard. I prefer to countersink the lower portion of the hole in the guard, so that the head will not project below the guard and catch upon obstructions, &c., and by making the enlarged portion 55 correspond with the shape of the head, which is preferably oval or angular, the bolt

can be tightened without applying any special means to the bolt-head for keeping it from turning around with the nut.

The nut which I prefer to use in connection 55 with the bolt consists of a hollow socket 8, the closed end of which 9 is formed into a head, which is preferably made beveled or inclined upon its inner portion to fit the correspondingly-flaring hole 4 in the ledger-plate. The 60 top of the head is provided with a slot or recess 10, which does not extend entirely to the edge at any point, thus presenting an unbroken outline all around the hole in the plate, and prevents the lodgment or entry of dirt, 65 &c., within the joint between the plate and the head of the nut. The interior of the socket is screw-threaded to correspond and engage with the threads of the bolt. To permit of the lower portion of the nut engaging 70 with the screw-threaded portion of the bolt, the upper portion of the hole in the guard is enlarged sufficiently to permit of the entry of the lower portion of the nut. The nut is cylindrical to permit of its free rotation in se- 75 curing the parts together. The holes can thus be made round, which permits of their being readily formed with a drill, and especially the upper enlarged portion of the hole in the guard.

If the guard is recessed below the ledger-plate, as shown at 10, the enlargement need 80 not be so extensive, or the recess can be made to take the place of or form the enlargement.

As above described, the ledger-plate can be quickly and firmly secured to the guard by 85 inserting the bolt from beneath until its head enters the enlargement in the hole, and the nut is then passed down through the ledger-plate until its lower end engages with the upper end of the bolt, when it is rotated until 90 the two have been drawn together to any desired extent.

Having described my invention, what I claim is—

The combination, with the finger-guard of 95 harvesters and mowers, having a vertical hole through it enlarged at its upper and lower portions, of a ledger-plate secured thereto, having a countersunk hole through it registering with the hole through the guard, a bolt 100 in the hole in the guard, the shank of which is screw-threaded and the head of which cor-

responds with and fits within the enlargement of the lower portion of the hole, and a hollow cylindrical socket, the interior of which is screw-threaded and engages with the upper 5 end of the bolt within the upper enlarged portion of the hole in the guard, and having its head beveled or inclined upon its inner surface, and having a slot or recess in its top for

rotating it which does not extend to the edge at any point, substantially as described. 10

In testimony whereof I affix my signature in presence of two witnesses.

DAVID WOEHRLE.
